UNITED STATES PATENT OFFICE.

WILFRED CHARLES KIMBER, OF WEST NORWOOD, LONDON, ENGLAND, ASSIGNOR TO
WALTER HADDON, OF LONDON, ENGLAND.

WIPING APPARATUS FOR PLATE-PRINTING MACHINES.

1,096,725.

Specification of Letters Patent.

Patented May 12, 1914.

Application filed February 18, 1913. Serial No. 749,190.

To all whom it may concern:

Be it known that I, WILFRED CHARLES KIMBER, a subject of the King of England, residing at West Norwood, London, England, have invented a certain new and useful Improved Wiping Apparatus for Plate-Printing Machines, of which the following is a specification.

The present invention relates to an improved wiping apparatus for plate printing machines and has for its object to provide for cleaning the plates or cylinders automatically and constantly, and at the same time more efficiently than has heretofore been possible.

The wiping apparatus according to the invention is of the type in which the printing plates are cleaned by a cleaning surface, such as a roller or an endless impervious band, to which there are applied supplementary cleaning devices, such as scrapers, to remove and collect the ink or color from the main cleaning surface and to clean the latter. In apparatus of this type it has been proposed that the wiping action shall be the resultant of two motions, namely a motion of translation of the wiper or of the plate, or of both of these parts, and a positive rotary or oscillating motion of the wiper itself, in a direction or at a speed other than that in or at which it would be driven by frictional contact with the printing plate, and this arrangement is adopted in the wiping apparatus according to the present invention.

According to one feature of the present invention the wiper comprises a resiliently-mounted roller between which and the printing plate there is translatory movement, said roller being positively driven in a direction or at a speed other than that in or at which it would be driven by frictional contact with the printing plate.

According to another feature of the invention the resiliently-mounted roller may be pneumatic. Other features of the invention relate to the mounting of the roller and to the construction and mounting of the scrapers which clean the wiping surface.

For a more complete understanding of the invention reference is directed to the accompanying drawings which show one embodiment of the invention by way of example.

In these drawings:—Figure 1 is an end elevation of the apparatus partly in section

on the line 1—1 of Fig. 3. Fig. 2 is a plan view of one end of the apparatus in section on the line 2—2 of Fig. 1 looking in the direction of the arrows *a*, and Fig. 3 is a side elevation of the apparatus partly in section on the line 3—3 of Fig. 1, and showing parts broken away.

Like letters of reference refer to like parts throughout the drawings.

The wiping apparatus illustrated comprises three wiping rollers A, B, and C the spindles A¹ B¹ and C¹ of which are carried in a frame-work D. The component parts of this frame-work are secured together by screwed bars D¹, and the spindles A¹ B¹ and C¹ are guided in slide-ways D² (see Fig. 1). For this purpose the ends of the spindles A¹ B¹ and C¹ carry box members E which fit between the slideways D².

To adjust the position of the spindles in the slideways rods F are provided. These rods F are screwed into the box members E at one end and at the other end project through the frame-work D to receive nuts F¹. The nuts F¹ are preferably knurled to provide for finger grip and have extensions F² which are guided in recesses in the frame-work.

The spindles A¹ B¹ and C¹ are resiliently mounted in the frame-work D for a purpose to be hereinafter described, springs G which encircle the rods F tending always to push the spindles A¹ B¹ and C¹ downwardly. The springs G each engage a box member E at one end and at the other engage a collar H¹ on a screwed sleeve H. The sleeves H surround and guide the rods F and are screwed into the frame-work D above the slideways D². Recesses H² in the collars H¹ are provided for adjusting the sleeves H in the frame-work and thus modifying the compression of the springs G. It will be seen that by this arrangement the rollers A, B and C can be pushed upwardly against the pressure of the springs G but that the limit of the downward movement of the rollers is determined by the nuts F¹.

The wiping rollers A, B and C shown in the drawings are composed of a core of wood or other suitable material and a leather, rubber-compound or like covering packed with some suitable soft material J, the ends of the rollers being provided with suitable closures, such as washers or flanges J¹. Referring to Fig. 2 it will be seen that

the spindles A^1 B^1 and C^1 carry gear wheels A^2 B^2 and C^2 respectively, the wheels A^2 and B^2 meshing with an idler wheel K and the wheels B^2 and C^2 meshing with an idler wheel L . The idler wheels K and L rotate loosely on studs K^1 and L^1 respectively which are screwed into the frame-work D . The wheel C^2 is driven by a wheel M^1 on a shaft M which may be carried by a bracket N supported from the frame-work D . The shaft M is driven in any suitable manner from the printing machine—for example by a chain and chain wheel, the direction of rotation in the example illustrated being such that the rollers A B and C are rotated in the direction shown by the arrows b Fig. 1.

Carried adjacent each wiping roller is a "doctor" or scraper P which at one edge bears on the surface of the wiping roller (see Fig. 1). Each scraper P , which extends throughout the length of the roller with which it cooperates, is mounted on a flat formed on a cylindrical bar Q and is secured thereon by screws Q^1 . The bars Q are each pivoted at each end in a box member Q^2 guided in slideways D^3 on the frame-work D in a somewhat similar manner to that in which the box members E hereinbefore referred to, are guided in the slideways D^2 . The box members Q^2 are provided with screwed rods R extending upwardly through the frame-work D and carrying outside the latter nuts R^1 . By this means the height of the scrapers P can be adjusted at will.

In the construction illustrated the scrapers P are not pressed downwardly by springs as are the rollers A , B and C , but another form of pressure device is employed. Bolted to the frame-work D by bolts S are channeled brackets T which extend throughout the length of the rollers A , B and C . The brackets T carry pressure bars U having knurled heads U^1 , these bars being preferably guided by one flange of the channeled bracket and screwed through the other flange, as clearly shown in Fig. 1. The lower ends of the bars U engage the scrapers P and press them onto the rollers A , B and C , the pressure being modified when the bars U are adjusted in position in the channeled brackets T .

Suspended in convenient positions relatively to the scrapers P are troughs V to receive the ink or color removed from the wiping rollers by the scrapers. These troughs V should preferably be mounted in such a way as to allow of being readily dismounted in order that they may be emptied or replaced by another trough. In the construction shown in the drawings the troughs V are each hung at one end on pins V^1 projecting from the frame-work D (see Fig. 2) and are provided at the other end

with a set-screw V^2 which is screwed into the frame-work D after the trough has been hung on the pins V^1 . The trough is thus securely held in position but may readily be dismounted by unscrewing the screw V^2 . 70

The operation of the apparatus is as follows:—As is well-known the usual plan is, when the plate or cylinder is engraved, to cover it with printer's ink or color which enters into the recessed or engraved portions, and then to rub off the ink from the plain part of the plate. To attain an efficient speed of working it is essential that the ink or color should be cleaned off the plain part of the plate automatically and constantly while the machine is at work, and this operation is effected very efficiently by the wiping apparatus according to the present invention. Referring to Fig. 1, the plate or cylinder being wiped, which is situated below the wiping apparatus, is, by the normal operation of the machine, moved in the direction of the arrow c Fig. 1 during the wiping operation, while the wiping apparatus is moved in the direction of the curved arrow d Fig. 1, the rollers A , B and C being rotated in the direction of the arrows b Fig. 1 as already stated. The wiping action of the rollers A , B and C on the plate is therefore the resultant of two motions, namely the motion of translation of the wiping apparatus (arrow d) and of the plate (arrow c), and of a rotary motion of the wiper rollers themselves (arrows b), this combined action giving very efficient results. It will be appreciated that the direct drive imparted to the rollers A , B and C is in the opposite direction to that in which the rollers would be rotated by reason of frictional contact with the plate during the wiping operation so that a scouring action is exerted on the plate. The motion imparted to the wiping apparatus as a whole (i. e. in the direction of the arrow d) will cause the roller A to roll first over the plate to be wiped. This roller will take up most of the ink or color and at the same time will be cleaned by its scraper P , the direction of rotation being such that a clean surface will always be brought into contact with the plate to be wiped. The second wiping roller B , completes the wiping and scouring effect while the roller C imparts a shine to the surface of the plate. The ink or color collected by the rollers A , B and C will be cleaned off by the scrapers P and transferred by the latter to the troughs V from which it may be collected and reused with or without a suitable preliminary cleansing or other treatment. The resilient mounting of the rollers A , B and C allows of any desired pressure being exerted on the plate or cylinder during the wiping action, and allows the rollers to adapt themselves to inequalities in the plates, while the adjust- 110

ability of the scrapers P allows of modification of the scraping action to suit different inks or different wiping surfaces, and also allows the rollers A, B and C to be dis-
5 mounted readily, since the pressure rods U can readily be slacked back and the scraper turned out of the way of the roller.

The nature and action of the leather, rubber-compound or like outer surfaces of the 10 rollers A, B and C is such that practically all the ink taken up by them from the plate or cylinder is cleaned off by the scrapers, this being a great improvement over the absorbent wipers sometimes employed, since 15 there is not the necessity to employ long bands of wiping material, small rollers as illustrated in the drawings being quite sufficient.

Many other modifications may also be 20 made within the scope of the present invention.

It will be seen that by the present invention not only is the surface of the plate cleaned while in use, but the cleaning surface itself (for example the rollers A, B and C) is also cleaned so that the cleaning surface can be used again and again. Moreover owing to the fact that a freshly cleaned 25 surface is always passing to the plate the latter is effectively wiped.

What I claim as my invention and desire to secure by Letters Patent is:—

1. Wiping apparatus for plate printing machines, comprising a framework adapted 35 to have a translatory movement over the plate to be wiped, a wiping roller mounted in and movable with said framework and having its axis lying transversely of the direction of movement of the framework, and 40 means carried by the framework for rotating said roller in the direction opposite to that in which it would be driven by frictional contact with the plate being wiped.

2. Wiping apparatus for plate printing 45 machines, comprising a framework adapted to have a translatory movement over the plate to be wiped, a plurality of wiping rollers mounted in and movable with said framework and each having its axis lying 50 transversely of the direction of movement of the framework, and means carried by the framework for rotating each of said rollers in the direction opposite to that in which it would be driven by frictional contact with the plate being wiped.

3. Wiping apparatus for plate printing machines, comprising a framework between which and the plate being wiped, there is adapted to be translatory movement, said framework having guideways, bearing blocks slidably mounted in said guideways, a wiping roller mounted on said bearing blocks, said roller having its axis lying transversely of the direction of relative movement between the framework and plate, rods ad-

justable in the framework and connected to said bearing blocks, a sleeve screwed into said framework and surrounding each rod and adapted to be adjusted in relation thereto, a spring on each of said rods bearing at one end against one of the aforesaid bearing blocks and at the other end against the aforesaid sleeve, a nut screwed onto each of said rods and having an extension received in and guided by a recess in the framework, 70 said nut, rod and bearing block being held under tension by said spring, and means carried by the framework for rotating said roller in the direction opposite to that in which it would be driven by frictional contact with the plate being wiped. 75

4. Wiping apparatus for plate printing machines, comprising a framework between which and the plate being wiped there is adapted to be translatory movement, said framework having guideways, bearing blocks slidably mounted in said guideways, a plurality of wiping rollers mounted on said bearing blocks, each of said rollers having its axis lying transversely of the direction of relative movement between the framework and plate, rods adjustable in the framework and connected to said bearing blocks, a sleeve screwed into said framework and surrounding each rod and adapted to be adjusted in relation thereto, a spring on each of said rods bearing at one end against one of the aforesaid bearing blocks and at the other end against the aforesaid sleeve, a nut screwed onto each of said rods and having an extension received in and guided by a recess in the framework, 85 said nut, rod and bearing block being held under tension by said spring, and means carried by the framework for rotating said rollers in the direction opposite to that in which they would be driven by frictional contact with the plate being wiped. 90

5. Wiping apparatus for plate printing machines, comprising a framework between which and the plate to be wiped there is adapted to be translatory movement, a wiping roller mounted in said framework and having its axis lying transversely of the direction of relative movement between the framework and plate, means carried by the framework for rotating said roller in the direction opposite to that in which it would be driven by frictional contact with the plate being wiped, a scraper blade carried by the framework and engaging with the surface of the wiping roller, a bracket adjustably mounted in the framework and extending over the scraper blade, and a plurality of rods adjustably carried by said bracket and engaging with said scraper blade to hold the same in engagement with the wiping roller under different tensions. 115

6. Wiping apparatus for plate printing machines, comprising a framework between 120

which and the plate to be wiped there is
adapted to be translatory movement, said
framework having guideways, a wiping
roller mounted in said framework and hav-
ing its axis lying transversely of the direc-
tion of relative movement between the
framework and plate, rods adjustable in the
framework and plate, means carried by the
framework for rotating said roller in the
direction opposite to that in which it would
10 be driven by frictional contact with the
plate being wiped, a bar mounted to have
movement in the guideways in the bracket,
means for adjusting said bar in said guide-
ways, a scraper blade carried by said bar
15 and adapted to engage the surface of the
wiping roller, a bracket adjustably mounted
in the framework and extending over the
scraper blade, and a plurality of rods each
20 of which is screw-threaded into said bracket
at one end and is plain at the other end
which is guided in the bracket and engages

with said scraper blade to hold the same in
engagement with the wiping roller under
different tensions.

7. In a wiping apparatus of the character
described the combination of a frame; means
mounted on the frame adapted to engage
with the surface to be cleaned; a bar mount-
ed on the frame; a scraper blade mounted 30
on said bar and adapted to engage with the
engaging surface of said means; means en-
gaging with said scraper blade for holding
the same in engaging position; and a trough
35 detachably mounted on the frame and dis-
posed beneath the scraper blade.

In testimony whereof I have signed my
name to this specification in the presence of
two subscribing witnesses.

WILFRED CHARLES KIMBER.
